UNITED STATES PATENT OFFICE.

CHARLES JOSEPH LANGENBACH, OF INDEPENDENCE, IOWA, ASSIGNOR OF ONE-HALF TO LOUIS F. SPRINGER, THOMAS SCARCLIFF, AND JASON F. VAN VORS, OF SAME PLACE, AND EARL KIEFER, OF MANKATO, MINNESOTA.

WINDMILL.

SPECIFICATION forming part of Letters Patent No. 659,372, dated October 9, 1900.

Application filed June 11, 1900. Serial No. 19,921. (No model.)

To all whom it may concern:

Be it known that I, CHARLES JOSEPH LANGENBACH, a citizen of the United States, residing at Independence, in the county of Buchanan and State of Iowa, have invented a new and useful Windmill, of which the following is a specification.

The invention relates to improvements in windmills.

10 One object of the present invention is to improve the construction of windmills and to provide a simple and comparatively-inexpensive one adapted to dispense with a vane and capable of holding the wind and of obtaining 15 a maximum effect therefrom.

A further object of the invention is to provide a windmill of this character which will be perfectly balanced and which will automatically govern itself and at the same time 20 be adapted to be readily thrown into and out of operation by hand.

The invention consists in the construction and novel combination and arrangement of parts hereinafter fully described, illustrated 25 in the accompanying drawings, and pointed out in the claims hereto appended.

In the drawings, Figure 1 is a vertical sectional view of a windmill constructed in accordance with this invention. Fig. 2 is a detail view of the wind-wheel, one half the 30 blades being arranged in position to be operated on by the wind and the other half being arranged out of operation. Figs. 3 and 4 are detail views illustrating the construction for transmitting motion from the vertical shaft 35 to the pump-rod.

Like numerals of reference designate corresponding parts in all the figures of the drawings.

40 1 designates a tower provided at its top with antifriction-rollers 2, arranged horizontally and receiving a rotary frame 3, which is provided with upwardly-extending arms 4 and 5, having bearings 6 and 7 for a horizontal wind-wheel shaft 8, and the latter extends from the 45 rotary frame in both directions and carries at one end a wind-wheel 9, and it has a counter-balancing-weight 10 at its other end, whereby the windmill is perfectly balanced and all

side draft is prevented. The rotary frame 50 depends within the tower and is provided with a depending tube 11, forming a housing for a vertical shaft 12, which is connected with the horizontal wind-wheel shaft by the means hereinafter described.

55 The end portion 13 of the horizontal wind-wheel shaft is provided with inner and outer annular flanges 14 and 15, from which extend arms 16 and 17, forming supports for pivoted blades 18, arranged at an acute angle to the 60 horizontal wind-wheel shaft and adapted to collect the wind. The inner arms 16, which are secured at their inner ends to the inner annular flange 14, are arranged at right angles to the horizontal wind-wheel shaft, and 65 they are provided at their outer ends with angularly-disposed eyes 19, which receive pintles 20 for hinging or pivoting the outer ends of the blades to the arms. The pintles 20, which may consist of bolts, pins, or any other suitable 70 fastening devices, also pass through eyes of straps 21, which are arranged at opposite sides of the eyes 19 of the arms 16. The blades are provided at their inner ends with longitudinal pintles 22, which are arranged in eyes or 75 openings of a bearing-ring 23, which is supported by the arms 17 of the outer flange 15 and by braces 24, extending from the ring to the inner flange, as clearly shown in Fig. 1 of the accompanying drawings. The blades by 80 being arranged at an acute angle to the shaft form a tapering space within them and are adapted to gather and hold the wind, and each blade is provided with a series of transverse slots or openings 25, arranged at an angle, as 85 shown, and adapted to permit currents of air to pass through the blades, and thereby enable the wind to obtain a hold or purchase on the same. The blades which are pivoted in this manner are adapted to be partly rotated to expose their faces to the wind and to arrange them edgewise to permit the wind to pass through the wind-wheel without rotating the same. This pivotal movement of the blades is effected automatically by means 90 of a weighted lever 26, which is connected by a coupling 27 with a series of rods 28, connected 95 at their outer ends eccentrically of the blades,

near the inner ends thereof, as clearly shown in Fig. 1. The blades are provided near their inner ends with eyes 29, receiving pintles 30, which pass through perforations or eyes of the outer ends of the rods 28, and the inner ends of the latter are connected with a flange or disk 31 of a section 32 of the coupling 27. The coupling 27 is composed of the said section 32 and a section 33, the section 32 being provided with the enlarged flange or disk 31 at one end, and it has a small annular flange 34 at its other end, and this small annular flange is received within an annular groove 35 of the section 33, whereby the section 32 is adapted to rotate within the section 33. The periphery or outer edge of the enlarged flange or disk 31 is bent or set at an angle to receive the inner ends of the rods 28, which are threaded for the reception of nuts 36, arranged in pairs and located at the opposite faces of the flange or disk 31. The inner section 33 is connected by a link 38 with one arm 39 of the lever 26, which is substantially T-shaped, being fulcrumed at 40 on a suitable support 41, extending from the adjacent arm 4 of the rotary frame. The arm 39, which is one of the transverse arms of the lever, extends upward from the bracket or support 41 to a point above the horizontal wind-wheel shaft, and the other transverse arm 42 extends downward from the bracket or support and is attached to a flexible connection 43, which passes over a guide-pulley 44 and extends downward to a sliding collar or sleeve 45. The sliding collar or sleeve 45, which has the lower end of the flexible connection attached to it, is slidingly mounted on the depending tube 11 and is provided with a pair of horizontal annular flanges 46, forming an annular groove in which extends a pin or projection 47 of a weighted lever 48. The weighted lever 48, which is fulcrumed between its ends on the tower, is provided at its outer end with a weight, and its other end is attached to a flexible connection 49, designed to extend to the base of the tower, so that the windmill may be controlled by hand. The pin or projection 47, which engages the annular groove of the sliding collar, is located at a point between the fulcrum of the lever and the flexible connection 49; but any other form of connection may be employed. The weight of the lever 48 is adapted to assist in sliding the collar upward after the flexible connection 49 has been slackened or released to start the windmill.

The horizontal wind-wheel shaft has keyed or otherwise secured to it a pair of vertically-disposed bevel gear-wheels 51 and 52, provided at their inner opposite faces with teeth and meshing with a pair of horizontal pinions 53 and 54, mounted, respectively, on the upper end of the vertical shaft 12 and on a vertical counter-shaft 55. The horizontal pinions 53 and 54 are provided with lower vertical spur-teeth and mesh with each other, and they have upper inclined teeth forming bevel-gear for

meshing with the vertically-disposed bevel gear-wheels 51 and 52. This double arrangement of gears is adapted to prevent all side draft and insures a smooth easy motion instead of the rough jerking movement common to many windmills.

The weight 10, which is of conical form, consists of a solid outer portion and a hollow inner portion forming a tapering sleeve or extension 56, which forms a continuation of the outer face of the solid portion of the weight 10 and which is extended sufficiently to form a shield for the gearing to prevent the same from obstructing the force of the wind. The conical weight is adapted to deflect the wind against the blades of the funnel or cup shaped wind-wheel. The adjacent end of the horizontal shaft 8 extends through the inner hollow portion or sleeve of the conical deflecting weight and is received within a socket 7 and is secured within the same by means of a set-screw, as clearly shown in Fig. 1. The weight, besides serving as a shield or deflector, is adapted to counterbalance the wind-wheel, and it co-operates with the double arrangement of gears in balancing the windmill and in preventing side draft.

The lower end of the vertical shaft 12 is provided with a horizontal pinion 59, which meshes with a vertical gear-wheel 60, as clearly illustrated in Fig. 3 of the accompanying drawings. These gears 59 and 60 are preferably beveled, as shown, and the vertical one is mounted on a horizontal shaft 61, which carries a vertical sprocket-pinion 62. The sprocket-pinion 62 is connected by a sprocket-chain 63 with an eccentrically-mounted sprocket-wheel 64, which is adapted to oscillate a horizontal lever 65. The horizontal lever 65, which is fulcrumed at one end, is provided at its other end with an opening or bifurcation 66 for the reception of the eccentrically-pivoted sprocket-wheel 64, and as the latter is rotated the horizontal lever will be oscillated. The horizontal lever is adapted to reciprocate a pump-rod 67, which is pivoted at its upper end to the horizontal lever at a point between the ends thereof. The weight of the pump-rod holds the chain or belt taut, and the stroke of the pump-rod is adjusted by means of a series of perforations 68, located at different distances from the center of the eccentrically-mounted gear-wheel 64 and adapted to receive the pivot 69 of the upper end of the pump-rod.

In order to guide the outer section of the coupling 27, it is provided with a pair of guide-rods 58, secured to the enlarged flange or disk 31 by nuts and extending through suitable openings or perforations of the inner flange 14.

It will be seen that the windmill is simple and comparatively inexpensive in construction, that there is no side draft, and that while it is automatic in its operation it is adapted to be readily thrown into and out of operation by hand. It will also be apparent

that the blades form a funnel or cup-shaped wind-wheel and that the slots or openings of the said blades permit currents of air through the same, and thereby tend to hold the wind 5 on the faces of the blades. Furthermore, it will be apparent that the conical deflector formed by the weight and the tapering tubular extension is adapted to direct the wind clear of the gearing and against the blades, 10 so that the latter will receive the full force and effect of the wind.

It will also be clear that a simple and effective device is provided for transmitting motion from the vertical shaft 12 to the vertically-reciprocating pump-rod, which is located 15 beneath the shaft, and that the stroke of the pump-rod may be readily varied, and that the weight of the said pump-rod retains the chain or belt in engagement with the eccentrically-mounted wheel of the oscillating lever. Also 20 this device may be mounted at any point on the tower and can be arranged close to the bottom thereof, so as to be readily adjusted.

What is claimed is—

25 1. In a windmill, the combination of a tower, a wind-wheel shaft extending horizontally from opposite sides of the tower, gearing arranged at the center of the shaft for transmitting motion therefrom, a wind-wheel 30 mounted on the shaft at one end thereof and provided with blades arranged at an angle or inclination and extending toward the tower to form a funnel or cup shaped space at the inner face of the wind-wheel, and a conical or 35 tapering counterbalancing-weight arranged at the other end of the wind-wheel shaft and forming a shield for the gearing and adapted to direct the wind upon the blades, substantially as described.

40 2. In a windmill, the combination of a rotary frame, a horizontal wind-wheel shaft journaled in suitable bearings of the frame, a

wind-wheel arranged at one side of the rotary frame and provided with blades set at an acute angle to the wind-wheel shaft to form 45 a funnel or cup shaped wheel, and a conical weight mounted on the other end of the wind-wheel shaft and provided with a tapering sleeve or extension forming a continuation of the side faces of the weight, substantially 50 as described.

3. In a windmill, the combination of a wind-wheel shaft, a wind-wheel arranged at one end of the shaft, and a conical weight located at the other end and provided with a tapering 55 sleeve or extension forming a continuation of the side faces of the weight, substantially as described.

4. In a windmill, the combination of a horizontal wind-wheel shaft, the inner and outer 60 flanges mounted on the shaft, the inner arms extending from the inner flange at right angles to the shaft, the outer arms extending from the outer flange and arranged at an angle, and the inclined blades supported by the 65 arms and extending toward the tower to form a conical or cup-shaped space at the inner face of the wind-wheel, substantially as described.

5. In a windmill, the combination of a horizontal wind-wheel shaft, a vertical shaft 12, 70 a short counter-shaft 55, horizontal pinions meshing with each other and mounted on the vertical shaft and the counter-shaft, and vertical gear-wheels carried by the horizontal 75 shaft and meshing with the pinions, substantially as described.

In testimony that I claim the foregoing as my own I have hereto affixed my signature in the presence of two witnesses.

CHARLES JOSEPH LANGENBACH.
